Attorney, Agent, or Firm—Eckert Seamans Cherin & Mellott

[57] CLAIM

The ornamental design for storm shutter, as shown and described.

DESCRIPTION

FIG. 1 is a front perspective view of storm shutter, showing my new design, wherein a window of a residential or commercial building is shown in broken lines to illustrate the operative environment thereof and forms no part of the claimed design;
FIG. 2 is a top plan view thereof;
FIG. 3 is a front elevational view thereof;
FIG. 4 is a rear elevational view thereof, partly broken away;
FIG. 5 is an enlarged view of the extreme lower right side of the storm shutter in FIG. 4, depicting a typical one of the cage nuts;
FIG. 6 is a left side elevational view thereof;
FIG. 7 is a right side elevational view thereof;
FIG. 8 is a bottom plan view thereof;
FIG. 9 is a bottom plan view of the top rail, with the overlapped corrugated panels removed;
FIG. 10 a top plan view of the bottom rail, with the overlapped corrugated panels removed;
FIG. 11 is a top plan view of the overlapped corrugated panels; and,
FIG. 12 is a bottom plan view of the overlapped corrugated panels.

Primary Examiner—Doris Clark
